UNITED STATES PATENT OFFICE

102,668

DESIGN FOR A COMBINED SWITCH PLATE AND THERMOMETER

Octavian Maximilian, Pittsburgh, Pa.

Application November 28, 1936, Serial No. 66,189

Term of patent 7 years

To all whom it may concern:

Be it known that I, Octavian Maximilian, a citizen of the United States, residing at Pittsburgh, in the county of Allegheny and State of Pennsylvania, have invented a new, original, and ornamental Design for a Combined Switch Plate and Thermometer, of which the following is a specification, reference being had to the accompanying drawing, forming a part thereof.

Fig. 1 is a front elevation of a combined switch plate and thermometer, showing my new design; and Fig. 2 is a cross sectional view taken on line II—II of Fig. 1.

I claim:

The ornamental design for a combined switch plate and thermometer, as shown.

OCTAVIAN MAXIMILIAN.
